WILLIAM J. STEINLE, OF ELMHURST HEIGHTS, NEW YORK, ASSIGNOR TO RUBBER
REGENERATING COMPANY, A CORPORATION OF INDIANA.

TIRE-BUILDING MACHINE.

1,252,049.

Specification of Letters Patent.

Patented Jan. 1, 1918.

Application filed September 24, 1915. Serial No. 52,351.

To all whom it may concern:

Be it known that I, WILLIAM J. STEINLE, a citizen of the United States, residing at Elmhurst Heights, L. I., county of Queens, State of New York, have invented certain new and useful Improvements in Tire-Building Machines, of which the following is a full, clear, and exact description.

This invention relates to tire building machines and has for an object to provide means whereby a definite percentage of stretch is given to the fabric as it passes to the tire forming core. A further object is to provide means for maintaining the percentage of stretch identical throughout the various plies.

In the manufacture of tires it is customary to produce a longitudinal stretch centrally in the flat fabric to conform the same to the rounded surface of the core. At present this is accomplished in various ways, as for instance, by retarding the roll feeding the fabric with a friction brake, or by a positive reduction drive of the feeding roll either from the core shaft or from the surface of the carcass.

Retarding the feeding roll by a brake is not satisfactory because a constant tension is produced on the fabric, hence the stretch in the outer plies of the carcass will be greater than that in the inner plies due to the increased diameter of successive plies exerting a corresponding increased pull upon the tensioned fabric. A positive reduction drive between the core shaft and feeding roll also increases the stretch of each successive ply by a small percentage over that of the underneath one owing to the increased diameter of the successive plies. A positive drive of the feeding roll from a friction wheel on the surface of the carcass nearly eliminates the increased stretch in the outer plies, but due to slip between the friction wheel and carcass the desired stretch in each ply is not positively assured, neither is an identical stretch produced throughout all the various plies.

To obviate the above disadvantages the present invention provides means for positively tensioning the fabric to a predetermined degree for the initial layer to obtain a definite percentage of stretch therein, and provides means for positively and automatically varying the tension to step increments corresponding to the increased di-

ameters of the successive plies to maintain said definite predetermined tension throughout the successive plies.

Preferably, the invention provides step cones and an inextensible connector which control the rotation of the fabric feeding roll. The fabric, while being taken on to the core, tends to rotate the feeding roll at a speed equal to that of the surface speed of the core. The inextensible connector unwinding from one step cone and winding up on the other step cone, allows the fabric feeding roll only to rotate at a definite speed less than the surface speed of the core. Since the fabric is extensible, and the connector is inextensible, the fabric receives a definite stretch equal to the difference between the length of the connector which the unwinding cone lets off and the particular circumference of the carcass, upon which a ply is being laid. The progressively changing diameters of the steps of the cone effect a speeding up of the feeding roll automatically at the completion of each ply to compensate for the increased diameter of the carcass. As a result of this changing of speed ratio to correspond to the position of any particular ply in the carcass, the stretch in the fabric is maintained identical throughout the various plies.

The invention can be readily understood from the following description taken in connection with the accompanying drawing, in which—

Figure 1 is a plan view of a tire building machine embodying my invention;

Fig. 2 is a side elevation of the parts shown in Fig. 1.

Referring now to the drawing in which like characters of reference designate similar parts, 10 designates a ring core of the usual and well known type which is preferably removably secured to a spider 11 that is power driven through the instrumentality of a shaft 12 and driven pulley 13, the shaft 100 being revolvably supported in a bearing 14 carried on a suitable frame 15.

A feeding roll 16 for the fabric is removably secured as shown at 17 upon a shaft 18 which is supported for rotation upon a suitable frame 19. The roll has preferably a surface configuration corresponding to that of the surface configuration of the core and is preferably of the same diameter as the core. Preferably a continuous strip of bias 110

rubber treated fabric 20 sufficient for a single tire is wound upon the roll at the bias cutting machine to minimize handling of the fabric before it is built into the carcass.

- 5 A step cone 21 is fixed to the ring core shaft 12 and a step cone 22 is fixed to the feeding roll shaft 18. An inextensible connector, such as a cable 23 connects the cones positively for simultaneous rotation. The 10 ends of the connector are securely fastened to their respective cones, and during rotation of the cone 21 on the core shaft the connector will be let off thereupon and spooled on the cone 22 on the feeding roll shaft. 15 In operation, the end of the fabric strip 20 is applied to the ring core to which it adheres and during each revolution of the core a ply of the fabric is drawn thereonto. The fabric thus forms a drive for the feeding 20 roll. The tendency of the fabric is to rotate the feeding roll at a speed equal to that of the surface speed of the core. However, as the inextensible connector unwinds from the step cone 21, and winds up on the step 25 cone 22, it allows the feeding roll only to rotate at a definite speed less than the surface speed of the core. The fabric being extensible, and the connector being inextensible, the fabric receives a definite stretch 30 equal to the difference between the length of the connector which the unwinding cone lets off and the circumference of the core.

The steps on the cone 22 decrease progressively in diameter in a direction outwardly 35 from the feeding roll, and are equal in number to the number of plies desired to be laid on the core. The steps on the cone 21 increase in diameter progressively in a direction outwardly from the core and are equal 40 in number to the steps on the pulley 22. Guide grooves 26 and 27 are formed in the steps of the cones respectively and direct the connector from one set of steps to the next succeeding set at the completion of 45 each revolution made by the core in taking on the fabric.

At the completion of the first ply of fabric on the core, the connector will be automatically directed by the guide groove from the 50 first set of steps to the next succeeding set of steps on the cones thereby permitting of the roll speeding up to deliver the fabric faster and thus compensate for the increased diameter of the first laid ply over that of the 55 core itself. At the completion of the second ply the connector is moved to the next succeeding set of steps, and so on until the desired number of plies have been laid. This 60 change in speed ratio to correspond to the position of any particular ply in the carcass serves to maintain the stretch in the fabric identical throughout the various plies.

I do not limit myself to the use of a pair of step cones as but one step cone may be 65 employed, and in lieu of the other a cylindri-

cal drum may be substituted. Furthermore I may vary the proportions, position of the steps, and make other changes in the construction of the cones themselves, where two cones are employed and may employ any 70 construction of connector so long as it is flexible and inextensible.

I believe that I am the first to conceive of automatically and positively varying the delivery of fabric to a tire forming core in 75 such manner that a predetermined definite stretch will be positively produced throughout the various layers superposed on the core, and I therefore consider that all and every apparatus accomplishing this result 80 falls within the scope of my invention.

What is claimed is:

1. A tire building machine comprising a power driven ring core, a fabric feed roll adapted to be driven by the feeding of the 85 fabric therefrom to the ring core, and means for positively retarding the speed of the feed roll relative to the ring core when the fabric is being applied, said means independently operating to increase the speed 90 of said feed roll relative to the said ring core at each revolution of the latter.

2. A tire building machine comprising a power driven ring core, a fabric feed roll adapted to be driven by the feeding of the 95 fabric therefrom to the ring core, and means mounted independently of the fabric for positively retarding the speed of the feed roll relative to the ring core when the fabric is being applied, said means independently 100 operating to increase the speed of said feed roll relative to the said ring core at each revolution of the latter.

3. A tire building machine comprising a power driven ring core, a fabric feed roll 105 adapted to be driven by the feeding of the fabric therefrom to the ring core, and means for positively retarding the speed of the feed roll relative to the ring core when the fabric is being applied, said means operating 110 independently of the fabric to increase the speed of said feed roll relative to the said ring core at each revolution of the latter.

4. A tire building machine embodying a power driven ring core, a fabric feeding roll, 115 a cone operatively connected with the core, a cone operatively connected with the feeding roll, said cones tapering oppositely from each other, and an inextensible flexible connector unwinding from the core cone and 120 winding up on the feeding roll cone.

5. A tire building machine embodying a power driven ring core, a fabric feeding roll, a step cone operatively connected with the core having steps which increase in diameter 125 progressively in a direction outwardly from the core, a step cone operatively connected with the feeding roll and having steps which decrease progressively in diameter in a direction outwardly from the feeding roll, and 130

an inextensible cable unwinding from the core cone and winding up on the feeding roll cone.

6. A tire building machine embodying a power driven ring core, a fabric feeding roll, a step cone operatively connected with the ring core, a step cone operatively connected with the feeding roll, an inextensible flexible connector unwinding from the core cone

and winding up on the feeding roll cone, ¹⁰ and guide grooves formed in the steps of each step cone to direct the connector from one set of steps to the next succeeding set at the completion of each revolution made by the core. ¹⁵

Signed at New York, N. Y., this 21 day of September, 1915.

WILLIAM J. STEINLE.
